US0D1077215S

(12) **United States Design Patent** (10) Patent No.: **US D1,077,215 S**
(45) Date of Patent: ** May 27, 2025

(54) **OXYGEN HOSE RETAINER**

(71) Applicants: **Phil DeJong**, Pueblo, CO (US); **Olivia DeJong**, Pueblo, CO (US)

(72) Inventors: **Phil DeJong**, Pueblo, CO (US); **Olivia DeJong**, Pueblo, CO (US)

(**) Term: **15 Years**

(21) Appl. No.: **29/923,796**

(22) Filed: **Jan. 2, 2024**

(51) LOC (15) Cl. **24-02**

(52) U.S. Cl.

USPC **D24/128**; D8/356

(58) **Field of Classification Search**

USPC D24/127-129, 229-231; D8/394, D8/338-339, 341-343, 382, 330-331, D8/347, 356

CPC A61M 5/1418; A61M 16/0875; F16L 3/13; F16L 3/22

(57) **CLAIM**

The ornamental design for an oxygen hose retainer as shown and described.

DESCRIPTION

FIG. 1 is a top front right perspective view of an oxygen hose retainer, showing our new design;

FIG. 2 is a front elevation view thereof, wherein a rear elevation view is a mirror image thereof;

FIG. 3 is a right elevation view thereof, wherein a left elevation view is a mirror image thereof; and,

FIG. 4 is a top plan view thereof, wherein a bottom plan view is a mirror image thereof.

1 Claim, 3 Drawing Sheets
